UNITED STATES PATENT OFFICE

JOHN STUBBS HOOKS, OF YAZOO CITY, MISSISSIPPI

DESIGN FOR A TOY ANIMAL

Application filed May 6, 1930. Serial No. 35,506. Term of patent 7 years.

To all whom it may concern:

Be it known that I, JOHN STUBBS Hooks, a citizen of the United States, residing at Yazoo City, in the county of Yazoo and State of Mississippi, have invented a new, original, and ornamental Design for a Toy Animal, of which the following is a specification, reference being had to the accompanying drawing, forming part thereof.

Fig. 2 is a side elevation thereof.

I claim:

The ornamental design for a toy animal, as shown.

JOHN STUBBS HOOKS.
